UNITED STATES PATENT OFFICE.

WILLIAM L. GARDNER, OF REDLANDS, CALIFORNIA.

PUMP-JACK.

1,289,436.

Specification of Letters Patent. Patented Dec. 31, 1918.

Application filed September 16, 1918. Serial No. 254,278.

To all whom it may concern:

Be it known that I, WILLIAM L. GARDNER, a citizen of the United States, residing at Redlands, in the county of San Bernardino and State of California, have invented 5 certain new and useful Improvements in Pump-Jacks; and I do declare the following to be a full, clear, and exact description of the invention, such as will enable others 10 skilled in the art to which it appertains to make and use the same.

My invention has for its object to provide a comparatively simple and inexpensive pump jack which will raise a great amount 15 of water with the expenditure of little power, no more power being necessary to operate a long stroke pump than a short one.

With the foregoing object in view, the invention resides in the novel features of construction and unique association of parts 20 hereinafter fully described and claimed, and shown in the accompanying drawings.

Figure 1 is a side elevation of the improved pump jack.

Fig. 2 is a horizontal section on the plane 25 of the line 2—2 of Fig. 1.

Fig. 3 is a vertical longitudinal section as seen on the line 3—3 of Fig. 2.

Fig. 4 is a vertical transverse section on 30 the plane designated by the line 4—4 of Fig. 1.

Fig. 5 is a detail vertical longitudinal section as viewed on the plane of the line 5—5 of Fig. 4.

35 In the drawings above briefly described, the numerals 1 designate a pair of sleepers upon which the ends of two parallel sills 2 are bolted or otherwise secured, the ends of said sills being preferably held in spaced 40 relation by transverse blocks 3 against the opposite ends of which they are secured by bolts or the like 4.

A pair of bearings 5 are secured to the upper edges of the sills 2, the outer end of each 45 bearing being provided with two vertical shoulders 6. Two pairs of vertical channel bars 7 are provided, one pair being located at the outer side of each of the sills 2 and having their inner flanges inset in said sills 50 and bolted thereto at 8. The free edges of said inner flanges abut the shoulders 6 as shown clearly in Figs. 1 and 2 and it will thus be seen that any tilting movement of the bars 7 longitudinally of the sills 2 will 55 be prevented. At their upper ends, the in-

ner flanges of the bars 7 are connected by tie bars 9 and the bars of the two pairs are similarly connected by other bars 10. Additional tie bars 11 may connect the lower ends of the outer flanges of the bars 7 and 60 in all cases, U-shaped bars 12 will be secured to said flanges adjacent their lower ends while arched bars 13 are secured in like manner to the upper ends of said flanges. Additional arched bars 14 may well be riveted at 65 15 to the inner sides of the bars 13 and project slightly beyond the inner edges thereof as shown in Figs. 1 and 4. Between the inner and outer flanges of the bars 7, anti-friction rollers 16 are mounted upon rivets 70 or the like 17 which pass through said flanges, and between the lowermost of these rollers, guide plates 18 are secured by bolts 19 in the channels of the bars and are spaced from the bottoms of said channels by spacing 75 blocks 20, so that the opposed sides of such plates are substantially flush with the peripheries of the rollers.

Pinions 21 are located between the plates 18 and a carrying shaft 22 is provided for 80 said pinions, said shaft being rotatably mounted in the bearings 5 and being driven in any preferred manner. For illustrative purposes, I have shown a relatively large gear 23 on the shaft 22 meshing with a 85 pinion 24 on a transverse drive shaft 25, the latter having a pulley 26 driven by a belt 27 from a suitable engine or the like. A vertical rack bar 28 is provided for each pinion 21, each of said rack bars consisting 90 of parallel side bars 29 and pins 30 extending between them, one side bar of each rack bar being longer than the other and being pivotally connected to the upper end of the pump rod 31. Each of the rack bars 28 is equipped with a lateral roller 32 on 95 its upper end, said roller being adapted to travel on the bars 13 and 14 when the rack bar has reached the limit of its upward stroke and is moved by the pinion from one track 7 to the other, and similarly the roller engages the U-shaped bar 12, when shifting of the rack bar takes place at the lower end of its stroke.

By constructing the device in the manner 100 shown and described, it may be easily and inexpensively manufactured and placed upon the market at minimum cost, yet in use it will be highly efficient and desirable. 105 By employing the invention, only about one- 110

tenth of the power heretofore necessary is required for raising water, and the power need not be increased as the stroke of the pump increases. Since probably the best 5 results are obtained from the details shown and described, they may well be followed, but within the scope of the invention as claimed, numerous minor changes may well be made.

10 I claim:

1. A pump jack comprising a sill, a pair of channel bars disposed vertically at one side of said sill with their inner flanges secured to the latter and with their channels 15 facing each other, a tie bar connecting the upper ends of said inner flanges, an arched bar connecting the upper ends of the outer flanges of said bars and a U-shaped bar connecting the lower ends of said outer 20 flanges, rollers mounted horizontally in the channels of said bars, a double-sided and double-ended rack bar operable between said channel bars, a driven pinion between said bars for moving said rack bar upwardly in 25 the channel of one bar and downwardly in the channel of the other bar, and a lateral roller on the upper end of said rack bar adapted to travel upon said arched and U-shaped bars when the rack bar is moved.

Copies of this patent may be obtained for five cents each, by addressing the "Commissioner of Patents, Washington, D. C."

from one track to the other at the completion of its strokes.

2. A structure as specified in claim 1, together with guide plates secured between the lower rollers and substantially flush with their peripheries to prevent the ends of 35 the rack bar from striking said rollers.

3. A pump jack comprising a sill, a bearing secured to the upper edge of said sill and having parallel vertical shoulders at one end, a pair of channel bars disposed 40 vertically with their channels facing each other, the inner flange of each bar contacting with one side of said sill and the edges of said inner flanges abutting said shoulders of the bearings to brace the bars, means for 45 securing said flanges to said sill, a vertical rack bar operable between said channel bars, a pinion meshing with said rack bar for moving it upwardly in one channel and downwardly in the other, and a carrying 50 shaft for said pinion mounted in said bearing.

In testimony whereof I have hereunto set my hand.

WILLIAM L. GARDNER.
